Primary Examiner — Richard E Chilcot(74) Attorney, Agent, or Firm — Justin A. Mark(57) CLAIM

The ornamental design for a home plate shaped waffle, as shown and described.

DESCRIPTION

FIG. 1 is a perspective view of a home plate shaped waffle showing my new design.

FIG. 2 is a top plan view thereof, the bottom plan view being a mirrored image thereof;

FIG. 3 is a front elevation view thereof;

FIG. 4 is a rear elevation view thereof; and,

FIG. 5 is a left side elevation view thereof, the right-side elevation view being a mirror image thereof.

1 Claim, 2 Drawing Sheets(56)
